C. COLLINS

HASP FASTENER

Filed July 10, 1922

UNITED STATES PATENT OFFICE.

CALHOUN COLLINS, OF BAKERSFIELD, CALIFORNIA.

HASP FASTENER.

Application filed July 10, 1922. Serial No. 573,807.

To all whom it may concern:

Be it known that I, CALHOUN COLLINS, a citizen of the United States, residing at Bakersfield, in the county of Kern and State of California, have invented certain new and useful Improvements in Hasp Fasteners; and I do declare the following to be a full, clear, and exact description of the invention, such as will enable others skilled in the art 10 to which it appertains to make and use the same.

This invention relates generally to fastening or locking devices for doors, gates, box lids and analogous devices, but it has particular reference to hasp fasteners which are especially adapted for use in connection with such devices.

The invention was designed in order to provide in a hasp fastener an improved 20 means for locking or coupling the hasp proper to the keeper in such a manner that the cooperating parts of the hasp and keeper will fit together even though the members upon which they are mounted may have 25 moved relative to each other such as where a door, gate, box lid or the like, sags, shrinks or swells.

The principles of the invention are applicable to hasp fasteners in which the 30 keeper is provided with a loop adapted to extend through a slot in one end of the hasp proper and to receive a padlock, and the principles of the invention are also applicable to hasp fasteners in which the hasp 35 itself carries a key-operated locking bar or bolt adapted to lockingly engage a portion of the keeper.

Devices embodying the principles of the invention may be made of cheap materials 40 and in a very simple manner, and hence they may be of very simple, cheap but nevertheless strong and durable construction, which are qualities that are desirable in devices of this character.

45 The novelty in the invention resides in the various details of construction and combination and arrangement of parts which are hereinafter specifically described and claimed and which are shown in the accompanying drawings.

In the accompanying drawings which form a part of this specification:

Figure 1 is a front elevation of hasp fastener in which the principles of the present 55 invention are embodied;

Figure 2 is a view of the upper edge of the hasp fastener, partly broken away and in section;

Figure 3 is a transverse sectional view taken substantially on the plane indicated by 60 the line 3—3 of Figure 1;

Figure 4 is a front view of the keeper plate of the hasp fastener;

Figure 5 is a front elevation of another hasp fastener in which the principles of the 65 present invention are embodied;

Figure 6 is a transverse sectional view of the hasp fastener illustrated in Figure 5, said view being taken substantially on the plane indicated by the line 6—6 of Figure 5; 70

Figure 7 is a longitudinal sectional view of the hasp fastener illustrated in Figure 5; and

Figure 8 is a detail perspective view of one of the parts of the hasp fastener illustrated 75 in the Figures 5, 6, and 7.

As hereinbefore explained the principles of the invention may be embodied in connection with a hasp fastener in which the hasp proper carries a locking bar or bolt 80 adapted to lockingly engage the keeper such as is shown in Figures 1 to 4 inclusive, and also in connection with hasp fasteners in which the keeper carries a loop adapted to extend through a slot formed in the hasp 85 proper and to receive an ordinary pad-lock or other suitable locking device, such as shown in Figures 5 to 8 inclusive.

In the embodiment of the invention illustrated in Figures 1 to 4 in the drawings, the 90 numeral 1 designates as a whole a hinge-hasp having an attaching leaf 2 hingedly connected at 3 to a swinging leaf 4. The leaf 2 is adapted to be secured by one or more screws, bolts or the like, to a door, gate, box 95 lid or analogous device, and in Figures 1 and 2 of the drawings the leaf 2 is shown as being secured by means of a screw 5 to a door D.

The swinging leaf 4 of the hasp is provided with a casing or housing 6 in which a suitable key-operated lock mechanism is mounted. To operate this mechanism a key may be inserted through the key-hole 7 formed in the outer side of the housing 6. 100 The lock mechanism may be of any suitable structure so long as it has a locking bar or bolt such as is represented by the numeral 8. The locking bar or bolt 8 shown in the drawings is fixed at its intermediate portion 105 110

to a pin or shaft 9 which projects from the rear of the housing 6 and hasp leaf 4 and which is adapted to be turned when the lock mechanism is operated by a key so that the bar 8 may be positioned so as to extend either longitudinally of the hasp leaf 4 or transversely of the latter.

The keeper for the hasp leaf 4 comprises a plate 10 adapted to be secured by means of screws, bolts or other suitable securing elements 11 to the door jamb J. This plate 10 has its side edges turned inwardly so as to form in the plate an undercut groove 12. The groove 12 is adapted to receive the locking bar 8 forming a part of the lock mechanism carried by the swinging leaf 4 of the hasp. When the bar 8 is positioned so as to extend longitudinally of the hasp leaf 4 it may pass into the groove 12. When the lock mechanism has been operated so as to swing the bar 8 transversely of the leaf 4, the bar 8 will have its ends engaged beneath the undercut portions of the groove 12 so as to lock the leaf 4 to the keeper plate 10.

In case the door D should sag, shrink or swell, and thus move relative to the jamb J, the cooperating parts of the hasp fastener will nevertheless fit together since the bar 8 may pass into the groove 12 at any place along the length of the latter. This is a decided improvement over the heretofore known and used devices of a similar character.

In Figures 5 to 8 inclusive of the drawings, the principles of the invention have been illustrated as embodied in connection with a hasp fastener in which an ordinary padlock P is used. In these views the numeral 13 represents the bar of a hasp.

The hasp bar is provided at one end with an aperture 14, through which one side of a staple 15 is passed to swingingly attach the bar to a door or the like represented by the letter D. The other end of the hasp bar 13 is provided with a longitudinally extending slot 16.

The keeper for the hasp 13 comprises one of the aforesaid plates 10 having an undercut groove 12 therein. The plate 10 is secured to the door jamb J or the like by means of screws 11.

Slidably mounted in the undercut groove 12 of the keeper plate 10 is a button or disk 17, to which is fixed an outwardly extending loop 18 adapted to pass through the slot 16 in the hasp bar 13 and to receive the padlock P.

The button 17 is not only slidably mounted in the groove 12 of the keeper plate 10 but is also turnably mounted, so that it may be slid along the groove 12 and turned in order to locate the loop 18 to extend through slot 16 in the hasp 13 regardless of whether or not the door D has sagged, shrunk or swelled.

From the foregoing description, taken in connection with the accompanying drawings, the construction, use and advantages of the invention will undoubtedly be understood so as to enable those skilled in the arts to which the invention appertains to make use of the same.

It is obvious that various changes in form, proportion and in the details of construction may be made without departing from the principles or sacrificing any of the advantages of the invention, and hence it is to be understood that such changes may be made within the scope of the appended claim.

I claim:

A keeper for a hasp comprising a plate adapted to be attached to a support and having a wide undercut groove therein, a button slidably and turnably mounted in said groove, and an outwardly extending loop fixed to said button and extending outwardly through the groove and moved to a desired angular relation to said plate through turning of the button in the groove.

In testimony whereof I have hereunto affixed my signature.

CALHOUN COLLINS.
